HAMMER MILL

Joseph A. F. Neal, Buffalo, N. Y.

Application July 20, 1939, Serial No. 285,529

4 Claims. (Cl. 83—11)

This invention relates to a hammer mill and more particularly to the type of hammer mill in which a plurality of hammers are swung from a rotating shaft to strike against an adjustable grinding plate installed in the casing of the mill.

One of the principal objects of the present invention is to provide such a hammer mill in which a plurality of fresh jagged cutting edges are presented by the grinding plate to the material being ground, regardless of the degree to which the grinding plate has worn. The maintenance of the grinding plate with a plurality of fresh jagged cutting edges throughout its life insures the rapid reduction of the material by the hammer mill.

Another object of the invention is to provide hammers in such a hammer mill which are similarly formed so as to always present fresh jagged cutting edges to the material to be ground regardless of the degree to which the hammers have worn.

Another object of the invention is to provide a hammer which is held in a fixed axial position on its hammer arm and each of which is at the same time so mounted as to present a new striking side to the grinding plate as the hammer wears, the mounting being also such that the hammers wear uniformly and do not require manual adjustment.

Another object of the invention is to provide such a hammer mill having the above features in which the hammers and grinding plates having the features embodying the invention can be provided without substantial increase in the cost of the hammer mill.

In the accompanying drawing:

Fig. 1 is an end elevation, partly in section, of the hammer mill embodying my invention.

Fig. 2 is a fragmentary enlarged vertical section of one of the hammers and the grinding plate.

Fig. 3 is a fragmentary horizontal section, taken on line 3—3, Fig. 1.

The invention is applicable to any usual and well known type of hammer mill, that shown including a casing 5 having an inlet 6 for the material to be ground and also having a central horizontal shaft 7 extending through the casing 5 and supported by bearings 8. The shaft 7 is rotated from any suitable power source (not shown) and within the casing 5 is shown as carrying a plurality of circular plates 9 which in turn carry a plurality of hammer arms 10. The hammer arms 10 are shown as pivotally mounted on pins 11 which extend transversely through the plates 9 parallel with the main drive shaft 7. The arms 10 are thereby free to swing around the pins 11

and in operation are thrown radially outward by centrifugal force as the main drive shaft turns.

Each of the hammer arms 10 carries one or more hammers 12 at its outer end, these hammers being of circular form and being mounted for free rotation at the ends of the hammer arms. For this purpose the hammers 12 are shown as mounted on pins 13 carried at the outer ends of the hammer arms 10. To insure free rotatability of the hammers 10, the pins 13 can be rotatably mounted in the ends of the hammer arms or the hammers 12 can be rotatably mounted on the pins 13 or both the hammers 12 and the pins 13 can be rotatably mounted. It is important, however, that the hammers 12 snugly fit the pins 13 and that these pins snugly fit the holes in the ends of the hammer arms so that the axes of the various hammers are held at a fixed distance from the axis of the main drive shaft 7 to secure the desired working efficiency. Each of the hammers 12 is shown as made of a circular disk of metal which is perforated throughout its entire area, as indicated at 14, the perforations 14 being closely spaced. The purpose of these perforations is to insure the maintenance of jagged cut edges in the hammer throughout its life and regardless of the degree to which the hammer wears.

The hammers 12 coat with a grinding plate indicated generally at 15. This grinding plate is arranged at one side of the casing 5 above the plane of the main drive 7 between horizontal shelves 16 and 17 in the casing. A cylindrical perforated plate 18 leads from the shelf 17 to a position under and adjacent the material inlet 6, an additional plate 19 being provided to insure the discharge of the materials into the cylindrical perforated plate 18 and against the grinding plate 15. The materials ground by the coaction of the hammers and the grinding plate 15 pass through the perforations of the cylindrical plate 18 to the bottom of the casing 5, the cylindrical perforated plate 18 being arranged concentric with the main drive shaft 7. The ground materials can be removed from the bottom of the casing in any suitable manner.

The grinding plate 15 is made up of a plurality of relatively thin metal plates 20 which are arranged face to face and the inner edges of which provide the grinding surface. Each of these plates is of the same size and form, their inner and outer edges thereof being concentric with the axis of the main drive shaft 7 and each of these plates 20 being made of perforated metal, the perforations being indicated at 21. As with the hammers 12, the purpose of so perforating the

several plates 20 comprising the grinding plate 15 is to insure the maintenance of jagged cutting edges in the working face of the grinding plate regardless of the degree to which this grinding plate wears.

In order to permit of the adjustment of the grinding plate 15 toward the axis of the main drive shaft 7 and thereby maintain the hammers and the grinding plate in the same spaced relation as wear takes place, the several sections 20 composing the grinding plate 15 are carried by a pair of horizontal bolts 25 extending through the upper and lower ends of the grinding plate sections 20 as shown in Fig. 1. Each of the bolts 25 extends through slots 26 in the casing 5, these slots being parallel and extending toward the main drive shaft 7. Upon loosening the nuts 27 of the bolts 25 the grinding plate 15 can be adjusted as a unit toward and from the main drive shaft 7 so as to permit of maintaining the desired space between the edges of the hammers and the jagged inner cutting surface of the grinding plate 15.

In operation the materials to be ground are introduced through the inlet 6 and the main drive shaft 7 is rapidly rotated so that the hammer arms 10 are swung radially outward. The materials introduced through the inlet 6 are subjected to grinding action between the hammers 12 and the grinding plate 15 and are reduced to a degree which permits their passage through the cylindrical perforated plate 18. As wear on any side of the hammers 12 takes place, a condition of unbalance is created which causes the heavier side of the hammer to swing to the outside and thereby present a fresh side to the grinding plate 15. This action takes place because the hammers 12 are freely rotatable about the axes of the pins 13 and hence as wear takes place on one side the opposite side is rendered heavier and hence swings around to coat with the grinding plate 15. At the same time the hammers 12 are held in fixed relation, axially, to the hammer arms on which they are mounted and hence act in the same manner as the rigidly mounted hammers heretofore provided.

As wear takes place on the grinding plate 15 or the hammers 12, the jagged cutting surfaces of this plate and the jagged edges of these hammers are maintained by the perforations provided. Thus, as the grinding plate 15 wears through one group of perforations 21 it wears through to the next succeeding group of perforations 21, the perforations being preferably closely spaced for this purpose. In a similar manner the perforations provided in the hammers 12 insure the presentation of fresh jagged edges to the material regardless of the degree of wear of the hammers. Both the grinding plate and the hammers can therefore be worn to a very substantial depth and at no time require sharpening or other treatment to insure their operation at full efficiency.

From the foregoing it will be seen that the present invention provides a hammer mill which is simple and inexpensive in construction; in which the hammers are held in fixed relation, axially, on the hammer arms so as to operate at full efficiency; in which the hammers wear uniformly and rotate to present a fresh edge as one side wears so that no adjustment of the hammers on the ends of the hammer arms need be provided and in which both the grinding plate and the hammers are so constructed as to always present jagged cutting edges to the mate-

rial to be ground regardless of the degree to which the grinding plate and hammers may be worn.

I claim as my invention:

5 1. A hammer mill comprising a casing having an inlet for the materials to be ground, a main drive shaft in said casing, a plurality of hammers carried by said drive shaft within said casing and a grinding plate assembly arranged to coat with said hammers to reduce said materials, said grinding plate assembly being composed of a plurality of arcuate plates provided with closely spaced perforations the axes of which are generally parallel with the axis of said main drive shaft, said plates being arranged face to face generally normal to the axis of said main drive shaft and with their edges facing said main drive shaft and means for holding said arcuate plates in assembled relation comprising upper and lower bolts extending through the upper and lower ends of said plates parallel with said main drive shaft, the ends of said bolts being received and secured in slots in said casing extending toward said main drive shaft whereby said bolts and the assembled plates carried thereby can be adjustably positioned along said slots concentrically toward and from said main drive shaft, the perforations of said plates providing a plurality of internal holes in said grinding plate assembly whereby the wearing of said grinding plate serves to continuously expose fresh jagged edges to said materials.

2. A hammer mill comprising a casing having an inlet for the materials to be ground, a main drive shaft in said casing, a plurality of hammer arms carried by said drive shaft within said casing, a hammer mounted on each of said hammer arms and a grinding plate arranged to coat with said hammers to reduce said materials, each of said hammers being composed of metal disks rotatably mounted on the end of the corresponding hammer arm and having a plurality of perforations extending therethrough parallel with said main drive shaft whereby the wearing of said hammers serves to continuously expose fresh jagged edges to said materials and said grinding plate being composed of a plurality of arcuate plates provided with closely spaced perforations the axes of which are generally parallel with the axis of said main drive shaft, said plates being arranged face to face generally normal to the axis of said main drive shaft and with their edges facing said main drive shaft and means for holding said arcuate plates in assembled relation comprising upper and lower bolts extending through the upper and lower ends of said plates parallel with said main drive shaft, the ends of said bolts being received and secured in slots in said casing extending toward said main drive shaft whereby said bolts and the assembled plates carried thereby can be adjustably positioned along said slots, the perforations of said plates providing a plurality of internal voids in the assembly of grinding plates whereby the wearing of said assembly serves to continuously expose fresh jagged edges to said materials.

3. A hammer mill comprising a casing having an inlet for the materials to be ground, a main drive shaft in said casing, a plurality of hammer arms carried by said drive shaft within said casing, a substantially circular disk forming a hammer and rotatably mounted at its center of gravity on the end of each of said hammer arms to rotate around a fixed axis arranged parallel with

the axis of said main drive shaft and a grinding plate arranged beyond said hammers to coat with said hammers to reduce said materials, said hammers being freely rotatable during the grinding operation whereby the wearing of one side of any hammer causes the hammer to rotate under centrifugal forces imposed thereon to present a fresh edge to said grinding plate and each of said hammer disks having a plurality of closely spaced perforations extending therethrough parallel with said main drive shaft whereby the wearing of said hammers serves to continuously expose fresh jagged edges to said materials.

4. A hammer mill comprising a casing having an inlet for the materials to be ground, a main drive shaft in said casing, a plurality of hammer arms carried by said drive shaft within said casing, a substantially circular disk forming a hammer and rotatably mounted at its center on the end of each of said hammer arms to rotate around a fixed axis arranged parallel with the axis of said main drive shaft and a grinding

plate arranged beyond and in opposing relation to said hammers to coat with said hammers to reduce said materials, said hammers being freely rotatable during the grinding operation whereby the wearing of one side of any hammer causes the hammer to rotate under the centrifugal forces imposed thereon to present a fresh edge to said grinding plate and said grinding plate being composed of a plurality of arcuate plates provided with closely spaced perforations the axes of which are generally parallel with the axis of said main drive shaft, said perforated plates being arranged face to face generally normal to the axis of said main drive shaft and with their edges facing said main drive shaft and means for holding said perforated plates in assembled relation, the assembled grinding plates being thereby provided with a plurality of internal holes whereby the wearing of the assembled grinding plates serves to continuously expose fresh jagged edges to said materials.
